DESCRIPTION

(56) **References Cited**

FIG. 1 is a front perspective view of a magnet for attachment to a capacitor;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a back perspective view thereof in a broken line environment.

The broken lines illustrate environmental features and form no part of the claimed design.
